(57) **CLAIM**

We claim the ornamental design for a shelf for a refrigerated
merchandiser, as shown and described.

DESCRIPTION

FIG. 1 is a perspective view of a shelf for a refrigerated
merchandiser according to the present invention.

FIG. 2 is a top view of the shelf shown in FIG. 1.

FIG. 3 is a front view of the shelf shown in FIG. 1; and,
FIG. 4 is a side view of the shelf shown in FIG. 1.
